Specification for Design.

Patented Feb. 12, 1918.

Application filed November 16, 1917. Serial No. 202,418. Term of patent 14 years.

To all whom it may concern:

Be it known that I, HENRY D'OLIER, Jr., a citizen of the United States, residing at Bridgeport, county of Fairfield, State of Connecticut, have invented a new, original, and ornamental Design for a Lamp-Socket Hood, of which the following is a specification.

My design is illustrated in the accompanying drawing, in which:

Figure 1 is a side elevational view of a hood for electric lamp sockets showing my new design.

Fig. 2 is a horizontal sectional view of the same below the cap.

I claim:

The ornamental design for a lamp socket hood, as shown.

HENRY D'OLIER, Jr.
